UNITED STATES PATENT OFFICE.

DAVID CRAIG, OF MELROSE, MASSACHUSETTS.

FAUCET.

974,028.

Specification of Letters Patent. Patented Oct. 25, 1910.

Application filed February 13, 1909. Serial No. 477,698.

To all whom it may concern:

Be it known that I, DAVID CRAIG, a citizen of the United States, and resident of Melrose, in the county of Middlesex and State of Massachusetts, have invented new and useful Improvements in Faucets, of which the following is a specification.

This invention relates to faucets, and particularly to faucets of the type in which the 10 spout is swiveled upon a fixture or frame containing the valve and valve casing, and the valve is opened or closed by swinging the spout itself to open or closed position.

In the accompanying drawings, which 15 illustrate one embodiment of my invention— Figure 1 is a front elevation of a faucet embodying my invention, showing the swiveled spout in closed position; Fig. 2 is a side elevation of said faucet showing the spout 20 in open position; and Fig. 3 is a vertical section through line 3—3 of Fig. 2.

The stationary part or frame of the device as shown consists of a yoke-like frame A having a standard or collar a, adapted to 25 rest upon the top of the usual slab adjacent to a basin, and an overhanging top part a'. An inlet passage a² which communicates with the supply pipe a³, extends through said frame. The upper part a' of the frame forms a 30 valve casing having therein the valve seat a⁴. The top of the valve casing is closed by the nut a⁵ provided with a bore or socket a⁶. A valve a⁷ of leather, rubber, fiber or other suitable material is mounted 35 on valve stem a⁸ between two collars a⁹ and a¹⁰. The upper part of the valve stem a⁸ extends into the socket a⁶ and is surrounded by coil spring a¹⁰ which abuts at one end 40 against the top of nut a⁵ and at the other end against the upper collar a⁹, normally urging the valve toward its seat a⁴. The lower end of valve stem a⁸ engages an abutment upon the swinging spout for the purpose presently to be described. The valve 45 seat a⁴ is carried by the externally threaded nut a¹¹ screwed into the internally threaded valve casing as shown. A guide is provided in nut a¹¹ for the lower end of valve stem a⁸ consisting of a ring a¹² which is supported by arms or spokes in a usual manner with the wall of the nut a¹¹. The outlet passage for the valve casing a' is through the 50 nut a¹¹.

The swiveled spout B comprises a vertical barrel part b and a laterally-extending noz-

zle b'. The barrel b is pivoted at its upper end in nut a¹¹, which is fast to the upper part of the frame, and at its lower end in collar a¹³, which is screwed to the frame above collar a. The barrel b is provided 60 with a partition b² below the entrance to nozzle b', and with an abutment b³ across the top of the barrel engaging the end of valve stem a⁸, and having apertures b⁴ connecting the valve chamber with the passage 65 through the barrel and nozzle.

a¹⁴ is a stuffing or packing nut.

On the top of collar a and within collar a¹³ is a cam a¹⁵ coöperating with a cam surface b⁵ on the lower end of the barrel b. 70 A coil spring b⁶ is secured at one end to the interior of barrel b and at the other end to the top of collar a.

Thus it will be seen that spout B may be 75 swung laterally, and is also movable longitudinally of its axis. When the spout is in normal or closed position as shown in Fig. 1, cam b⁵ rides down cam a¹⁵ allowing valve a⁷ to engage its seat a⁴ under the influence of spring a¹⁰. When the spout is swung to 80 open position, as shown in Figs. 2 and 3, the cam surface b⁵ rides up cam a¹⁵, thus lifting the spout longitudinally of its axis, and lifting the valve a⁷ from its seat through the abutment b³ and valve stem a⁸. The spring b⁶ is 85 thereby placed under tension and normally urges the spout toward its closed position, in which it is assisted by the normal tendency of cam surface b⁵ to slip down cam surface a¹⁵, and if the nozzle is released by the operator it will of itself fly back to closed position, 90 and there normally remain.

The nut or fitting a¹¹ carrying the valve seat a⁴ is removably or separably secured to the outlet end of the downwardly opening 95 valve chamber a' so that access may readily be had to the interior of the valve chamber for the purpose of cleaning or repairing the valve and valve seat. It will also be noticed that the valve stem a⁸ simply abuts against the end of the barrel b but is not attached thereto, so that the valve may be moved independently of the spout. If therefore it should be desired to empty the pipes of water, a vacuum may be created in passage 100 a³, a², on the inlet side of the valve, which would tend to lift the valve from its seat overcoming the resistance of spring a¹⁰ and 105 permit the water to be drawn off.

I claim:

1. A faucet comprising a yoke-like frame having an inlet passage therethrough, a valve chamber in said frame into which said inlet passage opens, an outlet passage 5 leading from said valve chamber, a valve in said valve chamber controlling said outlet passage, and a spout swiveled between the ends of said yoke-like frame, communicating with said outlet passage and controlling said 10 valve.

2. A faucet comprising a yoke-like frame, having an inlet passage therethrough, a valve chamber in said frame into which said inlet passage opens, an outlet passage leading 15 from said valve chamber, a valve in said valve chamber controlling said outlet passage, a spout swiveled between the ends of said yoke-like frame, communicating with said outlet passage and controlling said 20 valve, and means normally and yieldingly to urge said spout toward, and hold it in position to close said valve.

3. A faucet comprising a yoke-like frame having an inlet passage therethrough, a valve chamber in the upper end of said frame 25 into which said inlet passage opens, an outlet passage leading from said valve chamber, a valve in said valve chamber controlling said outlet passage, and a spout swiveled 30 between the ends of said yoke-like frame, communicating with said outlet passage and controlling the operation of said valve.

4. A faucet comprising a yoke-like frame having an inlet passage therethrough, a valve chamber in the upper end of said frame 35 into which said inlet passage opens, an outlet passage leading from said valve chamber, a valve in said valve chamber controlling said outlet passage, and a spout communicating 40 with said outlet passage, swiveled between the ends of said yoke-like frame, means to move said spout longitudinally of its axis when it is swung laterally, and connection between said spout and valve where- 45 by such movement of the spout longitudinally of its axis will control the opening and closing of said valve.

5. A faucet comprising a yoke-like frame having an inlet passage therethrough, a valve chamber in the upper end of said frame 50 into which said inlet passage opens, an outlet passage leading from said valve chamber, a valve in said valve chamber controlling said outlet passage, a spout communicating 55 with said inlet passage, swiveled between the ends of said yoke-like frame, cam surfaces upon said spout and frame respectively adapted to move said spout longitudinally of its axis when it is swung later- 60 ally, and connections between said spout and valve whereby such movement of the spout longitudinally of its axis will control the opening and closing of said valve.

6. A faucet comprising a yoke-like frame having an inlet passage therethrough, a 65

valve chamber in the upper end of said frame into which said inlet passage opens, an outlet passage leading from said valve chamber, a valve in said valve chamber controlling said outlet passage, and a spout 70 communicating with said outlet passage, swiveled between the ends of said yoke-like frame, cam surfaces upon said spout and frame respectively adapted to move said spout longitudinally of its axis when it is 75 swung laterally, and connections between said spout and valve whereby such movement of the spout longitudinally of its axis will control the opening and closing of said valve and a spring normally and yieldingly 80 to urge said spout toward, and hold it in, position to close said valve.

7. A faucet comprising a valve casing having an inlet passage and an outlet passage, a normally closed valve in said casing 85 controlling said outlet passage, a swiveled spout communicating with said outlet passage, said valve having a valve stem engaging an abutment upon said swiveled spout, and means to move said spout longitudinally 90 of its axis when it is swung laterally and thereby to operate said valve through said valve stem.

8. A faucet comprising a yoke-like frame having an inlet passage therethrough, a valve chamber in the upper part of said frame 95 into which said inlet passage opens, an outlet passage leading from said valve chamber, a valve in said valve chamber, having a downwardly extending valve stem, a 100 spout communicating with said outlet passage swiveled between the ends of said yoke-like frame, an abutment carried by said spout and engaging said valve stem, and means to move said spout longitudinally of 105 its axis when it is swung laterally, and thereby to operate said valve through said abutment and valve stem.

9. A faucet comprising a yoke-like frame having an inlet passage therethrough, a valve chamber in the upper part of said frame 110 into which said inlet passage opens, an outlet passage leading from said valve chamber, a valve in said valve chamber, having a downwardly extending valve stem, a 115 spout communicating with said outlet passage swiveled between the ends of said yoke-like frame, an abutment carried by said spout and engaging said valve stem, means to move said spout longitudinally of 120 its axis when it is swung laterally, and thereby to operate said valve through said abutment and valve stem, and means normally and yieldingly to urge said spout toward, and hold it in position to close said valve. 125

10. A faucet comprising a yoke-like frame having an inlet passage therethrough, a valve chamber in the upper part of said frame into which said inlet passage opens, a valve in said valve chamber, a removable 130

fitting secured to the outlet side of said valve casing having thereon a valve seat provided with an outlet passage therethrough controlled by said valve, a spout

5 comprising a hub part and a nozzle part, the hub part communicating with said outlet passage and swiveled between said removable fitting below said valve seat, and the lower end of the yoke-like frame, and

means controlled by the movement of said 10 swiveled spout to operate said valve.

Signed by me at Boston, Massachusetts, this fifth day of February, 1909.

DAVID CRAIG.
